E. W. VEST.

GAS BURNER FOR FURNACES, STOVES, AND RANGES.
APPLICATION FILED APR. 8, 1918.

1,325,456.

Patented Dec. 16, 1919.

UNITED STATES PATENT OFFICE.

EUGENE W. VEST, OF ST. LOUIS, MISSOURI.

GAS-BURNER FOR FURNACES, STOVES, AND RANGES.

1,325,456.

Specification of Letters Patent. Patented Dec. 16, 1919.

Application filed April 8, 1918. Serial No. 227,244.

To all whom it may concern:

Be it known that I, EUGENE W. VEST, a citizen of the United States, residing at St. Louis, in the State of Missouri, have invented certain new and useful Improvements in Gas-Burners for Furnaces, Stoves, and Ranges, of which the following is a specification containing a full, clear, and exact description, reference being had to the accompanying drawings, forming a part hereof.

My invention relates to an improved gas-burner for furnaces, stoves, and ranges, and it consists in the novel construction herein-after fully described, and as particularly pointed out in the claims found at the end of this specification.

The object of my invention is to provide improved devices for utilizing in a very efficient and economical manner the gas that passes into the burner; and to improve upon the devices for controlling the "primary" and "secondary" air that are shown and described in a companion application, entitled Gas-burning system for furnaces, heating-stoves, ranges, &c., filed by me on April 8, 1918, the same date that the present application was filed, Serial No. 227,245; whereby a maximum of heat will be produced with the expenditure of a minimum quantity of gas.

In the drawings,

Figure 1 is a sectional side-elevation of my improved burner applied to the fire-box and ash-pit of a common furnace, stove, or range. Fig. 2 is a detail front elevation of one of the handles of the gas-valve stem, and its immediate connections, detached.

Fig. 3 is a detail view in perspective of the combustion-chambers of three burners, arranged "tandem," as they are in the fire-box of a range, and

Fig. 4 is a plan view of the arrangement of refractory parts used in one form of fire-boxes.

The numeral 1 designates the outer wall of the range, furnace, or stove in which my invention is to be used, and 2 designates the bottom of the ash-box or ash-pit of either of such apparatus, or it may be the ash-box or ash-pit of a hot-water heater, or of a hot-water heating-boiler, or the base of a steam-boiler furnace.

The fire-box is, in the present instance, divided up into a plurality of small combustion-chambers (or spaces) 3, which are made

in rectangular form by suitable horizontal base-sections 4 made of iron or other proper material, and placed end-to-end with their abutting ends or edges connected by overlapping or rabbeted parts to form a tight joint, as designated by the numeral 5, and supported by brackets or angle-bars 6 located in said ash-box at suitable points; top-sections 7 of highly refractory material (such as fire-clay) placed end-to-end with their abutting ends connected by overlapping parts and supported a proper distance above the said base-sections by blocks of refractory material 8, which not only support said top-sections but act as partitions between the adjacent combustion-chambers 3, the said top-sections being seated in recesses 9 formed in the upper edges of the said supporting and partitioning blocks 8, so that the upper surface of said top-sections will lie flush with the upper edges of the said blocks, which are set on edge, and stand in a vertical position; the opposite sides of said combustion-chambers being closed by side-sections 10, the abutting ends or edges of which are united by rabbeted or overlapping joints, as with the previously mentioned sections.

The said side-sections 10 are of sufficient height for the purpose mentioned, and in some cases they may extend past the end blocks 8 a sufficient distance to receive a number of filling-blocks 11 between them at one or both ends of the fire-box, and an end-piece 12 may extend across one end of the side-sections 10, for the purpose of filling in any space in the fire-box that is not occupied by or as a combustion-chamber.

The said top-sections 7 are purposely made so narrow that a passage or space 13 is left between the opposite edges of said sections and the adjacent upper edges of the said side-sections 10, to form exit-passages for the flame and hot gases from said combustion-chambers to a fire-chamber 14 located above the latter, and in which fire-chamber 14 there is placed (in the present instance) a body of what are known in the art as fire-clay "biscuits" 15, which rest upon and are supported by the said top-sections 7.

The numeral 16 designates the top of the range, or the top of said fire-chamber 14, no matter what form of apparatus my invention may be located in, whether it be in a range, furnace or stove, there being a suit-

able space left above the said "biscuits" 15 (or other similar small pieces of hard refractory material) for the free passage of the hot expanded gases to some other portion of the range after they have passed through the interstices of said "biscuits" on their way to the smoke-pipe or other destination.

A vertical secondary-air pipe 17 surrounds 10 the vertical discharge-pipe 18 of the mixing-tube 19 of each combustion-chamber, said discharge-pipes 17 and 18 being united in a single casting, and the open upper ends of said discharge-pipes project upwardly 15 through an aperture 20 formed in the base-section 4 of said chamber, so that the mixture of gas and air from said discharge-pipe 18, as well as the air from the said discharge-pipe 17, will be discharged upwardly into 20 said combustion-chamber, and the flame will impinge upon the underside of the said top-sections 7 of the burner, and then pass upward into and through the body of "biscuits" 15, and thence to some other part of 25 the range or other apparatus; the said gas and air being thoroughly commingled and burned in a most economical manner, my improved construction (as shown and described) enabling me to heat the said "biscuits" to from 1000° to 1500° Fahrenheit, and to pass through the interstices of such 30 highly heated refractory material necessary quantities of secondary air that is not used in completing the combustion, and to discharge such air against the top (or carry it to other parts) of the range or other apparatus, there to part with its heat in useful 35 work.

The burner casting, of which said discharge-pipes 17 and 18 form a part, is supported by suitable means, such as a pedestal 21, the lower end of which rests upon the bottom 2 of the ash-pit, while its upper end carries a common T 22 which is threaded 45 into a tubular boss 23 formed integral with the lower portion of said casting, and the interior of which boss communicates with the interior of a dirt-receptacle 24 in communication with the lower end of said central discharge-pipe 18, whereby the dirt and dust which accumulates in said dirt-receptacle may be removed by inserting a small scraper through the clean-out pipe 25 connected to said T and extending horizontally 50 to a point adjacent the front of the range or other apparatus, and thereat provided with a removable cap 26, for an obvious purpose.

The said mixing-tube 19, and the gas-valve 60 thereof, may be of any common approved form; but preferably they are of one of the forms shown and described in my above-mentioned companion applications, wherein the horizontal portion of the gas-valve casting, 65 as 27, is connected to the outer end of said

mixing-tube by means of a common coupling, as 28, to conduct the mixture of gas and air to the said discharge-pipe 18.

The said gas-valve casting has mounted in it the usual gas-valve stem 29 having a handle 30 fixed upon its outer end, to control the entrance of gas to said mixing-tube 19, the gas reaching the interior of said casting by way of a pipe 31, common union 32, and common gas-cock 33 connected to the service 75 pipe 34.

The air-throat 35 of the said gas-valve casting has its interior in communication with the interior of the said horizontal portion 27, which is of course in communication 80 with the interior of the said mixing-tube 19.

Simultaneous regulation of the entrance of air to said air-throat 35 and the passage of gas to the said mixing-tube, is secured by a slide-valve 36 having an aperture 37 which 85 registers with the entrance to said throat when said throat is opened by said valve, and is mounted to slide in suitable guides 38 across the entrance to said throat, and a suitable connection between said gas-valve 90 stem 29 and the said valve, which will cause said stem and valve to move in unison; whereby the turning up or down of the gas will at the same time regulate the air, to produce the Bunsen flame required for the 95 most efficient and economical operation of the burner.

As herein shown, and as more specifically shown and described in my companion applications, previously mentioned, I have provided a cam, as 39, which is fixed upon the gas-valve stem 29 at a point between the stuffing-box gland 40 and the stem handle 30, the projecting lip 41 of said cam being embraced by a U-shaped bearing 42 at the 105 lower end of a vertical shank 43 at the lower edge of said valve 36; whereby when the said stem is rocked or partially rotated the cam will cause a corresponding movement of said valve, and more or less close or open 110 the entrance to the said air-throat.

Common lighting means are provided, in the form of lighter-tubes 44 having the usual lighter-tips 45, some of said tips having a lateral tip 46 for communicating the flame 115 to the next adjacent tip of the series, for lighting the burners in the usual manner, the said lighter-tubes being connected to said service pipe 34 and provided with a common shut-off cock 47 for controlling the supply of gas to said lighter tips.

At the lower end of the burner casting is an integral valve or damper chamber 48, the entrance of which has mounted in or over it a common damper 49, which is provided with a crank or lever 50.

Said damper or valve lever 50 is connected to the handle or lever 51 of the said service-pipe gas-cock 33 by a horizontal rod 52, one end of which is pivoted at 53 to the said 130

air-entrance damper-lever 50 while its opposite end is adjustably and pivotally connected to the said gas-cock lever 51 by the following means in the present case:

- 5 The free end of the stem 54 of said gas-cock 33 is squared or otherwise made non-cylindrical, and the said gas-cock lever 51 is formed with a corresponding socket or bearing 55, which is fixed upon the said stem 54, and the latter is provided with a series of perforations 56, some of which are located nearer the inner end of said lever 51 than are the other perforations.

10 A sleeve 57 having a handle 58 by which it may be grasped and moved, and having a perforated ear 59 is slidably mounted upon the said gas-cock lever 51, and the outer end of the said horizontal rod 52 is pivotally connected at 60 to the said perforated ear 20 of said lever.

The said slidable sleeve 57 is provided with perforations, as 61, in its opposite sides which register with the desired perforation 56 of the said gas-cock lever 51, in 25 adjusting the sleeve upon said lever, the said registering perforations being occupied by a common pin 62, which is secured to the said lever by means of a chain 63 and screws or other fastening-means 64, to provide 30 against the accidental misplacement of the said pin.

When it is desired to adjust the said sleeve 57 upon the said gas-cock lever 51, to impart a greater or less movement to the said 35 damper 49, it is only necessary to slide the sleeve to the desired position and secure it there by inserting said pin 62 in the proper registering perforations of the sleeve and the lever.

40 It will thus be seen that I have provided a means for mechanically regulating the supply of secondary air to the burner, simultaneously with the regulation of the gas-supply to said burner; whereby the secondary-air entrance chamber 48 is throttled against the passage of too much cold air at all times, to correspond to the amount of gas being used, and a very high efficiency and economy are accomplished, inasmuch as 45 much unnecessary cold air is excluded from the fire-box, and the latter is retained at all times at the highest temperature consistent with the quantity of gas being burned.

The movement of the said gas-cock 51 50 toward the right-hand should open the gas-cock 33 and simultaneously open a corre-

sponding distance the said cold air damper 49 of the burner casting, while a reverse movement of such connected parts will have the opposite effect on both the gas supply 60 and the air supply, with the resultant economy and efficiency, as before recited.

The operation of the other parts of my invention will be readily apparent from the above description, and need not be further 65 elucidated.

I claim the following:

1. A fire-box divided into a plurality of small combustion-chambers by horizontal base-sections, top-sections, vertical partitions, and side-sections; said sections being united to like sections by overlapping joints, and said base-sections having an aperture through which the gas and air enters, and all of said sections being made of highly 75 refractory material except said base-sections.

2. A fire-box divided into a series of small combustion-chambers of rectangular form having their top and sides made of refractory material, and having an aperture in 80 their bases; a burner-casting arranged to discharge a mixture of gas and air through said aperture of said bases; a fire-chamber above the series of combustion-chambers, there being passages for the gases and flame 85 between said combustion-chambers and the said fire-chamber; and a body of refractory material in small pieces located in said fire-chamber.

3. In a gas-burner for furnaces, stoves and ranges, a casting having concentric discharge-pipes for the air and gaseous fuel; a mixing-tube; a gas-valve for regulating the supply of gas to said mixing-tube; a service-pipe gas-cock having a rockable stem 90 and handle; an air entrance at the base of said burner casting separate from the mixing-tube entrance; a means which opens and closes said air entrance in said base; and an adjustable connection between said air entrance controlling means at the base of said casting and said handle of the said service-pipe gas-cock, for simultaneously controlling the passage of gas and cold air to the 95 burner.

In testimony whereof, I have signed my name to this specification in presence of two subscribing witnesses.

EUGENE W. VEST.
